UNITED STATES PATENT OFFICE

164,006

VACUUM BOTTLE CLOSURE

William Axline Laird, Long Beach, and Phillip L. Greathead, South Gate, Calif.; said Greathead assignor to said Laird

Application June 9, 1950, Serial No. 10,432

Term of patent 14 years

(Cl. D58—26)

To all whom it may concern:

Be it known that we, William A. Laird and Phillip L. Greathead, citizens of the United States, residing at Long Beach and South Gate, respectively, State of California, have invented a new, original, and ornamental Design for a Vacuum Bottle Closure, of which the following is a specification, reference being had to the accompanying drawing, forming a part hereof.

Figure 1 is a perspective view of a vacuum bottle closure showing our new design with the stopper removed;

Figure 2 is a perspective view of the closure with the stopper positioned therein;

Figure 3 is a side elevational view of the closure;

Figure 4 is a rear elevational view of the closure; and

Figure 5 is a plan view of the closure.

The dotted lines shown in Figures 1, 2 and 3 are for illustrative purposes only.

We claim:

The ornamental design for a vacuum bottle closure, as shown and described.

WILLIAM AXLINE LAIRD.
PHILLIP L. GREATHEAD.
